DESIGN FOR A FLOWER VASE

Alexander F. Richards, Mayport, Pa.

Application December 11, 1943, Serial No. 111,988

Term of patent 14 years

To all whom it may concern:

Be it known that I, Alexander F. Richards, a citizen of the Dominion of Canada, residing at Mayport, in the county of Armstrong and State of Pennsylvania, have invented a new, original, and ornamental Design for Flower Vase, of which the following is a specification, reference being had to the accompanying drawing, forming part thereof.

I claim:

The ornamental design for a flower vase, as shown.

ALEXANDER F. RICHARDS.
